(57) **CLAIM**

The ornamental design for a vehicle body, as shown and described.

DESCRIPTION

FIG. 1 is a front perspective view of a vehicle body showing our new design.

FIG. 2 is a rear perspective view thereof.

FIG. 3 is a right side view thereof.

FIG. 4 is a left side view thereof.

FIG. 5 is a front view thereof; and,

FIG. 6 is a rear view thereof.

It will be understood that the top is plain and unornamental and further that the broken line shown throughout the drawings is for illustration only, forming no part of the claimed design.

UNITED STATES PATENT AND TRADEMARK OFFICE
CERTIFICATE OF CORRECTION

PATENT NO. : Des. 463,758 S
APPLICATION NO. : 29/133768
DATED : October 1, 2002
INVENTOR(S) : Meadows et al.

Page 1 of 7

It is certified that error appears in the above-identified patent and that said Letters Patent is hereby corrected as shown below:

IN THE DRAWINGS:

Replace drawing sheets 1-5 with the following sheets 1-5.

Replace title page with attached title page.

Signed and Sealed this

Nineteenth Day of September, 2006

A handwritten signature in black ink, appearing to read "Jon W. Dudas". The signature is written in a cursive style with a large, stylized "J" and "W".

JON W. DUDAS
Director of the United States Patent and Trademark Office
